UNITED STATES PATENT OFFICE

ISIAH CONRAD, OF COLUMBUS, OHIO, ASSIGNOR TO F. O. SCHOEDINGER, OF COLUMBUS,
OHIO

SHEET-METAL FURNITURE

Application filed August 8, 1925. Serial No. 49,099.

This invention relates to sheet metal furniture, and has for its primary object the provision of an improved corner post by means of which facility and economy can be obtained in the uniting of adjacent angularly disposed walls in the manufacture of such furniture, a strong and substantial construction produced and an appearance of simplicity and good taste presented.

With these and other objects in view, as will appear as the description proceeds, the invention consists in the novel features of construction, combinations of elements and arrangements of parts hereinafter to be fully described and pointed out in the appended claim.

In the accompanying drawing:

Figure 1 is a perspective view of a table or stand provided with the corner posts formed in accordance with the present invention,

Figure 2 is a vertical longitudinal sectional view taken through one of the posts on the plane indicated by the line 2—2 of Figure 3,

Figure 3 is a horizontal sectional view on the line 3—3 of Figure 2, and

Figure 4 is a similar view on the line 4—4 of Figure 2.

Referring more particularly to the drawing the numeral 1 designates a table or stand of sheet metal construction, the same in this instance being formed to comprise a plurality of vertically disposed corner posts 2, a top 3, side and end walls 4 and 5 respectively and a shelf 6 located contiguous to the body of the stand and disposed between the corner posts 2.

Each corner post comprises a tubular hollow sheet metal body 7, which terminates in angularly disposed flaring wings 8, which are positioned to lie flatly in engagement with the adjoining surfaces of the walls 4 and 5, and by means of which the said walls 4 and 5 may be secured to the corner post either by spot-welding or any other equivalent union. The wings 8 may engage either the inner or outer surfaces of the walls 4 and 5, depending upon the desired appearance which is to be given the finished article. Similarly, in connecting the shelf 6 with the posts, the

wings 8 engage the side walls of said shelf and are either spot-welded or riveted thereto as desired. In this instance the wings 8 extend substantially throughout the height of the posts, so that the shelf 6 may be positioned and secured in any desired horizontal plane throughout the height of the posts, or the walls 4 and 5 may be of any desired depth. The lower ends of the posts, in this instance, are provided with tubular extensions 9, arranged for the reception of bearing sleeves 10, in which are received the vertical shanks 11 of casters 12.

In view of the foregoing it will be seen that the present invention provides a corner post particularly useful in the manufacture of sheet metal furniture or other sheet metal articles or receptacles. The post so formed produces a construction of very considerable mechanical strength and finishes an article of furniture in such a manner as to render the same attractive. By virtue of the securing means 8 convenience, permanency and economy are obtained in associating metallic walls with the posts, accomplishing this end in a positive mechanical manner, without detracting from the appearance of the article and in a quick, labor-saving economical method.

What is claimed is:

An article of furniture of the character described, formed of metal, including a plurality of vertically extending corner members each formed to provide a tubular body having a longitudinally extending opening in one side thereof and a flat longitudinally extending angularly disposed integral wing extending outwardly from each vertical edge of the opening and at right angles one to the other, a top supported by the corner members, the lower ends of the tubular bodies being formed and adapted to receive the shanks of casters, and a horizontally extending member supported by and between the corner members, the wings of the corner members extending parallel with and engaging the marginal edges of the horizontally supported member for a substantial distance and the corners of the supported member extending through the longitudinally extend-

ing openings of the corner members to be received within the tubular body portions thereof, the vertical edges of the openings engaging the marginal edges of the horizontally extending member.

5 In testimony whereof I affix my signature.

ISIAH CONRAD.
